UNITED STATES PATENT OFFICE

148,289

DESIGN FOR A BENCH

Edward W. Discher, Milwaukee, Wis.

Application September 3, 1946, Serial No. 133,037

Term of patent 14 years

(Cl. D15—11)

To all whom it may concern:

Be it known that I, Edward W. Discher, a citizen of the United States and resident of Milwaukee, in the county of Milwaukee and State of Wisconsin, have invented a new, original, and ornamental Design for a Bench, of which the following is a specification, reference being had to the accompanying drawing, forming part thereof.

The figure is a perspective view of the bench showing my new design.

I claim:

The ornamental design for a bench, as shown.
EDWARD W. DISCHER.
